UNITED STATES PATENT OFFICE.

HARRY WESTROPP ARMSTRONG, OF HAMILTON, ONTARIO, CANADA.

DRAFTING APPARATUS.

1,187,881.

Specification of Letters Patent. Patented June 20, 1916.

Application filed October 16, 1914. Serial No. 866,965.

To all whom it may concern:

Be it known that I, HARRY WESTROPP ARMSTRONG, a subject of the King of Great Britain, residing at 39 Duke street, in the 5 city of Hamilton, county of Wentworth, Province of Ontario, Canada, have invented certain new and useful Improvements in Drafting Apparatus, of which the following is a specification.

10 In making of mechanical, architectural and other drawings, extensive surfaces require to be covered with section lining or other conventional details indicating the material, surface finish, ornamentation, and 15 the like. All this at present is drawn by hand, using pen or pencil, which involves the expenditure of a large amount of time.

My object is to devise means whereby such conventional details may be rapidly and 20 effectively filled in without the necessity of drawing in each mark or line by pen or pencil.

I accomplish my object by providing a series of plates, preferably of some stiff flexible material, each plate having formed thereon in strong relief a "positive" representation of draftsman's conventional detail work, each differing in the character of the representation thereon. These plates are used by 30 placing them under the tracing paper or linen on which the drawing is being made, and by taking an impression of the raised design by rubbing the surface of the drawing with crayon or pencil.

35 The details of the process are hereafter more specifically described, and the apparatus and work done thereby are illustrated in the accompanying drawings in which—

Figure 1 shows a face view of part of a 40 wall of a building showing details which may be produced by my device; Fig. 2 a cross section of the same wall; Figs. 3 and 4 plan views of two of the plates constructed in accordance with my invention; Figs. 5 45 and 6 plan views of similar plates provided with means for joining them side by side; Figs. 7, 8 and 9 cross sections on an exaggerated scale showing different forms of section for the raised lines on the plates; and 50 Fig. 10 a perspective view of a clip used for joining two plates together.

In the drawings like numerals of reference indicate corresponding parts in the different figures.

55 1 are the plates, which are preferably of some stiff moderately hard and moderately

thick material. While a good quality of cardboard or any other material possessing the necessary characteristics is more or less satisfactory, celluloid or xylonite will 60 usually be employed. Each plate has formed thereon in strong relief a representation of conventional detail work such as employed by draftsmen.

By conventional detail work is to be 65 understood any design that requires to be constantly repeated to indicate different classes of material and surfaces of same, such as brick and stone work, concrete, timber, etc., in section, plan and elevation, shading such as used to represent curved surfaces, and all repeated designs or 70 ornamentations. For example, in Fig. 3 is represented section lining such as commonly employed to indicate sections of glass, brick or 75 stone. In Fig. 4 is represented a brick surface, in Fig. 5 a surface shading of parallel lines such as may be employed on stone surfaces, and in Fig. 6 is represented concrete work in section.

80 It will be noted that the design on each plate is a "positive", that is, it corresponds exactly with the reproduction instead of being a "negative" like an electrotype with the design reversed as to position as in a 85 photographic negative.

The raised lines are preferably formed without producing corresponding depressions on the back of the plate, that is to say, the designs are preferably not embossed, but will be applied to the surface of the plate so that the back of any plate is a plane surface. When so constructed the raised lines possess a very desirable rigidity and stiffness. In cross section the raised 90 parts may vary according to the nature of the representation. For fine section lining, for example, the section may be triangular as shown in Fig. 7, for sharp clear heavy section lining the quadrilateral form shown 100 in Fig. 8 may be employed, the angles being sharp, and for soft effects rounded corners 105 may be employed as shown in Fig. 9.

It is found in practice that the relief of the design should not be less than 1/100 of 105 an inch and that all parts of the face of the design should reach substantially the same plane, so that adjacent lines are substantially the same distance from the back of the plate. Each plate is surrounded by 110 a plain margin or border almost flush with or at any rate but slightly below the sur-

face of the design, which is of importance, as it prevents the edges of the design being chipped and supports the tracing paper beyond the design so that no tendency exists 5 for the edges of the design to be brought out too prominently during the rubbing process.

The plates are employed by bringing one 10 of appropriate design below the part of the drawings to which the design is to be applied. An oil crayon is then rubbed over the surface of the drawing paper, whereupon the design appears on the surface of the paper rubbed. Any light transference 15 of the crayon which may take place between the lines may then readily be removed by lightly rubbing with a suitable drawing cleaning rubber. A roller of said composition is found to be most satisfactory for 20 removing such superfluous matter. There is then left on the drawing a clear representation of the desired details, slightly fainter, however, than the ink drawn lines of the drawing. The sectional and surface representations 25 are thus slightly subordinate to the outlines, which is a very desirable feature, particularly in architectural work.

In order to enable the plates to be moved readily beneath a large drawing, each plate 30 is preferably provided with small pieces 2 of a magnetic metal such as iron or steel. These are embedded or otherwise secured in the plates, preferably at each side, and are spaced so that any pair may be attracted by 35 the poles of a horse shoe magnet acting through the drawing from above. To facilitate the plates being easily moved by such means they are provided both on their top and bottom surfaces with small raised knobs, 40 one in each corner, which reduces friction with the paper above and the table beneath.

It will sometimes be necessary to fit two or more plates together so that different representations may be reproduced exactly 45 fitted to one another in a predetermined position. For this purpose certain of the plates may have the representation carried right out to one edge, as shown in Figs. 5 and 6, and the edges of the plates designed 50 to fit together provided with suitable means for connecting the plates in the desired relationship. In these figures of the drawings, I show bent clips 3 secured to the

edges of one of the plates in such a manner that the edges of the adjacent plate may be 55 slipped in to them. Any other means, of course, may be provided for this purpose.

To facilitate the lifting of the plates, thumb notches 4 are provided preferably one at each side of each plate. The plates, 60 for indexing purposes, are numbered at their upper right hand corners so that they may be readily kept in a card file for convenient access.

It will be understood of course that there 65 is no limit to the different representations that may be applied to plates. A complete set will necessarily contain similar representations on different scales. Different sets may also be provided according to the class 70 of drawing for which it is to be used, an architect's set differing from that supplied for the use of a mechanical draftsman.

What I claim as my invention is:—

1. Drafting apparatus comprising a stiff 75 hard plate having formed thereon raised lines in strong relief forming a "positive" representation of draftsman's conventional detail work surrounded by a plain border adapted to form a support for superimposed 80 tracing material beyond the margins of the design.

2. Drafting apparatus comprising a series of stiff hard plates each having formed thereon in strong relief a positive representation of draftsman's conventional detail work surrounded by a plain border 85 adapted to form a support for superimposed tracing material beyond the margins of the design and each differing in the character 90 of the representation thereon.

3. Drafting apparatus comprising a stiff hard plate with a plane back having formed on its face in strong relief a "positive" representation of draftsman's conventional 95 detail work surrounded by a plain border adapted to form a support for superimposed tracing material beyond the margins of the design.

Signed at Toronto, Canada, this 10th day 100 of October, 1914, in the presence of the two undersigned witnesses.

HARRY WESTROPP ARMSTRONG.
